CLAIM

The ornamental design for a rail for an archery bow, as shown and described.

DESCRIPTION

FIG. 1 is a front, right perspective view of an archery bow having an integrated rail;

FIG. 2 is a front view thereof;

FIG. 3 is a back view thereof;

FIG. 4 is a side view thereof;

FIG. 5 is a side view thereof;

FIG. 6 is an enlarged front perspective view thereof;

FIG. 7 is an enlarged side view thereof;

FIG. 8 is an enlarged side view thereof;

FIG. 9 is an enlarged partial front view thereof; and, FIG. 10 is an enlarged cross-sectional bottom view of a portion thereof.

The evenly spaced broken lines depict environmental structure of the rail for an archery bow that form no part of the claimed design. The long-dash, short-dash, short-dash broken lines depict boundaries of the claim, which boundaries form no part of the claimed design. The long-dash, short-dash broken lines—which form the extent of the enlarged views—form no part of the claimed design.
